UNITED STATES PATENT OFFICE

ERNEST G. DANIELSON, OF SAN FRANCISCO, CALIFORNIA, ASSIGNOR TO GRAY & DANIELSON MANUFACTURING COMPANY, OF SAN FRANCISCO, CALIFORNIA, A CO-PARTNERSHIP CONSISTING OF ERNEST G. DANIELSON AND THOMAS B. GRAY

VARIABLE TUNING DEVICE

Application filed July 13, 1927. Serial No. 205,341.

This invention relates generally to devices for effecting tuning of electrical circuits, and is particularly adapted for use with radio receiving systems.

5 It is an object of this invention to devise a manual control for a variable tuning instrument, which will be simple in construction, will eliminate all back lash and will be smooth in operation.

10 It is a further object of this invention to devise a convenient mounting for a variable tuning instrument which will incorporate a novel form of manual control.

15 It is a further object of this invention to devise a novel form of indicating drum for a variable tuning device.

20 Further objects of this invention will appear from the following description in which I have set forth the preferred embodiment of my invention. It is to be understood that the appended claims are to be accorded a 25 range of equivalents consistent with the state of the prior art.

Referring to the drawings:

25 Figure 1 is a top plan view illustrating a tuning instrument provided with a control constructed in accordance with this invention.

Fig. 2 is a side elevational view of the tuning instrument shown in Fig. 1.

30 Fig. 3 is a front view of the tuning instrument and its control, with the instrument being mounted behind an instrument panel.

Fig. 4 is a cross sectional view taken along the line 4-4 of Fig. 1.

35 In the mounting of variable condensers or other tuning devices behind the front panel of a receiving cabinet, it has previously been proposed to arrange the condenser in such a way that its shaft is parallel to the plane of

40 the instrument panel and then to manually rotate the condenser shaft by means of a rotatable control shaft extended thru the panel. This arrangement is usually utilized with a drum type of indicator having a minor portion

45 of its periphery visible thru a window in the instrument panel. It is advisable to have the control shaft located comparatively close to the panel window, but in order to prevent 50 the operator's hand from obstructing the view

of the indicating drum, it is advisable to offset the control shaft either above or below the window. A variety of mechanisms have been employed for operatively connecting the instrument shaft to the rotatable control shaft, as for example belts and pulleys, chains and sprockets, and worm gear drives. The belt and pulley mechanism is objectionable since the flexible cord or belts employed must be replaced at frequent intervals and slippage 55 may occur if the belt stretches sufficiently. The chain drive gives a jerky, uneven movement to the instrument shaft, while both the chain and worm drives provide an excessive amount of back lash. In this invention these 60 difficulties have been eliminated by the use of a simple helical gear and pinion. A drive connection of this kind is not only cheaper to manufacture, but it also possesses inherent characteristics which make it particularly 65 adaptable for use as a control for a variable tuning instrument.

70 Referring to the drawings for a complete description of the invention, there is shown a variable tuning instrument 10, as for example a variable condenser of the type such as disclosed in my Patent No. 1,589,946 issued June 22, 1926 and entitled Variable condenser. A condenser of this type includes a pair of electrodes 11 which are pivotally mounted on a suitable insulating base 12. These electrodes are caused to move relative to each other by use of a pair of intermeshing gears 13, which in turn are rotated by means of a pinion 14 secured to a rotatable instrument shaft 16. 75

80 In order to conveniently support the variable tuning instrument 10 behind an instrument panel 18 of a radio receiving set, there is provided a metal plate 19 to which the insulating base 12 is secured as by means of 85 screws 21. The plate 19 is preferably reinforced as by means of integral flanges 22 formed along the edges of the same, and is also provided with an integral flange 23 whereby the plate may be secured to the rear side of the instrument panel 18 in such a position that it extends substantially perpendicular thereto. The instrument shaft 16 projects thru the plate 19 normally thereto and accordingly is arranged substantially 90 95 100

parallel to the instrument panel 18 when the tuning unit is operably mounted within a radio receiving cabinet.

Positioned upon the instrument shaft 16, 5 there is a gear wheel 24 which is preferably formed of a piece of sheet metal pressed to provide a peripheral flange 26. Upon the edge of flange 26 and therefore forming a face for the gear, are the gear teeth 27 which are 10 preferably formed helical. Gear 24 is removably secured to the instrument shaft 16 as by means of set screw 28. The gear 24 and shaft 16 are adapted to be manually rotated by means of a rotatable control shaft 31 which 15 preferably extends adjacent one side of plate 19 and parallel thereto. One end of shaft 31 is journaled within a ferrule 32, this ferrule being threaded into the struck in portion 33 of flange 23, and the other end of the shaft 20 is retained between a pair of integral struck out projections 34. The bearing for this portion of the shaft is formed by a journal block 36 which is slidably retained between the projections 34. Positioned upon the control 25 shaft 31 so as to mesh with the gear 24, there is a gear of pinion 37 which is likewise provided with helical teeth. Gears of this type are called twisted gears. A leaf spring 38 is provided which presses against the journal block 36 and serves to resiliently urge the pinion and gear together, thus eliminating all back lash. That end of the shaft 31 which projects thru the instrument panel 18, may 30 be provided with convenient control knob 39. 35 In order to aid in keeping the pinion in perfect mesh with the gear 24, the shaft 31 is preferably interrupted and a suitable flexible coupling 41 is inserted to interconnect the adjacent shaft ends. This coupling for example 40 may be in the form of a tightly wound helical spring as shown, the ends of the spring being secured to the adjacent shaft ends.

With the arrangement such as described above it will be noted that the control shaft 45 31 is offset a substantial distance from the axis of the instrument shaft 16. In some instances it is desirable to place the control shaft 31 above the instrument shaft 16 or to invert the plate 19 and still have the control 50 shaft 31 below the instrument shaft. To permit this result, the plate 19 is provided with duplicate means for journaling the shaft 31 upon either side of the instrument shaft. Thus the plate has been shown as provided 55 with an internally threaded portion 133 corresponding to the threaded portion 33 previously described, and also with integral struck out projections 134 similar to the projections 34 previously described.

60 In order to provide convenient means whereby the operator may judge the relative position of the instrument shaft 16, there is provided an instrument drum 43 which is rotatable with shaft 16 and which has its 65 periphery visible thru a window 44 in the

instrument panel 18. A convenient way to construct this indicating drum is to provide a pair of metal discs 46 retained apart in spaced relationship as by means of spacing members 47. Spacing members 47 likewise 70 serve to permanently secure the drum to one face of the gear 24. The peripheral edge of each disc 46 is bent to provide an inwardly faced groove 48, these grooves serving as a means for slidably engaging the edges of a 75 flexible indicating strip 49. This indicating strip is shown in Fig. 1 and preferably contains graduations 51 of any desired character. It is preferably provided with an inscribable surface whereby any desired legends may be written directly upon it thru the window 44. Where the ends of the indicating strip 49 overlap as shown in Fig. 1, the discs 46 are preferably provided with aligned slots 52 whereby one end of the strip 80 may be engaged and pulled outwardly so that the entire strip may be slid within the grooves 48 and thereby removed from the drum. A new indicating strip may then be inserted thru the slots 52 and slid about the 85 drum until it occupies the desired position.

The window 44 thru which the indicating drum is viewed, is preferably formed in an inset portion 54 of a metal plate 56. In order to illuminate that portion of the drum which is viewed, there may be provided a small electric lamp globe 57 inserted in a suitable socket 58 which is mounted upon one of the flanges 22 of plate 19. A slight space is left between the inner edges of the inset portion 54 and the periphery of the indicating drum, and light 57 is positioned directly above or below the inset portion 54 so as to project its light down between this portion 54 and the drum periphery, thus affording 100 105 an indirect lighting effect.

It will be obvious from the above description that I have provided a simple and effective control for the variable tuning instrument, which may either be sold separately for use with any standard tuning instrument or which may be sold together with a tuning instrument as a complete unit. If desired the control device may also be incorporated with a plurality of tuning instruments so as to form what is commonly known as a gang control. To facilitate coupling of one or more additional instruments to the shaft the indicating drum 43 is provided with an aperture 61 whereby the shaft of another instrument may be coupled to an axial stud 62 provided on the hub of gear 24. The inclined or helical shape of the gear teeth afford a sliding action which makes the control perfectly smooth and even. The teeth need not be machine cut but may be pressed into the edge of flange 26 by a knurling tool.

I claim:

1. In a device of the class described, a 130

- plate adapted to be secured to an instrument panel, a variable tuning instrument mounted on one side of the plate, said instrument having a rotatable shaft projecting thru the 5 plate, a control shaft disposed substantially parallel to said plate and offset to one side of said instrument shaft, means formed on said plate for journaling said control shaft, drive means for operatively connecting said 10 shafts, and additional means formed upon said plate for journaling said control shaft upon the opposite side of said instrument shaft.
2. A mounting and control for a variable 15 tuning device comprising a plate to which said device can be mounted, said device having a rotatable shaft adapted to project thru said plate, a rotatable control shaft, a pair of spaced members mounted on said plate 20 and forming a slot within which said control shaft is journaled, said control shaft extending substantially at right angles to the shaft of said device, a gear fixed to the shaft of said device, a pinion on said control shaft, 25 and resilient means normally urging the control shaft in a direction to force said gear and pinion into engagement.
3. In a device of the class described, a plate 30 adapted to be disposed at substantially right angles to an instrument panel, a variable tuning instrument mounted on one side of said plate, said instrument having a rotatable shaft projecting thru the plate, a control shaft disposed substantially parallel to said 35 plate and offset to one side of said instrument shaft, means formed on said plate for journaling said control shaft, drive means operatively connecting said shafts, and additional means mounted on said plate for journaling 40 said control shaft upon the opposite side of said instrument shaft.
4. In a radio receiver the combination with 45 a front panel having control means thereon, of tuning means to the rear of said panel, a drum member carrying indicating means on its circumferential periphery, said drum member being coupled with tuning means, a circular flange formed along the base of said drum member, and offset from the outer 50 periphery of said drum member, a shaft extending from said control means through said panel, and driving means on the shaft, co-acting with said flange, whereby to actuate said drum and said tuning means.
5. In a radio receiver the combination with 55 a front panel, having control means thereon, of tuning means to the rear of said panel, a drum member carrying indicating means on its circumferential periphery, said drum 60 member being coupled with said tuning means, a circular flange formed along the base of said drum member and offset from the outer periphery of said drum member, a shaft extending from said control means 65 through said panel, and driving means on
- the shaft, coacting with said flange, whereby to actuate said drum and said tuning means, and means for maintaining the pressure of said driving means, whereby to provide for constant contact of the same against the 70 flange on said drum.
6. In a radio receiver, the combination with a panel, of control means to the front of said panel, a shaft fixed to the control means and passing to the rear of said panel, 75 tuning means to the rear of said panel, a drum member carrying indicating means on its circumferential periphery, said drum being coupled with tuning means and positioned to the rear of said panel, an aperture in said panel through which a portion of said indicating means may be visible, and an annular projection formed on the base of said drum adjacent the circumferential periphery thereof, and means on said shaft for contacting 80 with said projection, whereby to actuate the drum member and the tuning means.
- In testimony whereof, I have hereunto set my hand.
